The ornamental design for an image projection prism, as shown and described.

DESCRIPTION

FIG. 1 is a front perspective view showing an image projection prism of the present invention;

FIG. 2 is a rear perspective view thereof;

FIG. 3 is a front view thereof;

FIG. 4 is a rear view thereof;

FIG. 5 is a right side view thereof;

FIG. 6 is a left side view thereof;

FIG. 7 is a top view thereof;

FIG. 8 is a bottom view thereof;

FIG. 9 is a cross-sectional view taken along lines 9-9 in FIG. 7;

FIG. 10 is a cross-sectional view taken along lines 10-10 in FIG. 3; and,

FIG. 11 is a cross-sectional view taken along lines 11-11 in FIG. 3.

The oblique line shading showing of image projection prism is included for the purpose of illustrating transparent or translucent surfaces.
